HAIR CLIPPER

James Catina, Philadelphia, Pa.

Application July 25, 1938, Serial No. 221,197

1 Claim. (CL. 30—214)

My invention relates to improvements in clippers and more particularly to that class utilized for trimming human hair.

One of the principal objects of my invention is to provide a clipper so constructed and arranged as to trim hair in a manner to effect the desired taper to the hair to conform to the contour of the head whereby to present a neat and attractive appearance.

10 Another object of my invention is to provide a device of the above described character which is simple in construction, durable in use, efficient in operation and economical in manufacture.

Other objects and advantages will be apparent 15 from the following description, appended claim and annexed drawing.

Referring to the drawing wherein like reference characters designate like parts throughout the several views:

20 Figure 1 is a longitudinal sectional view of my invention.

Figure 2 is a top plan view thereof.

Figure 3 is a sectional view taken on the line 3—3 of Figure 1.

25 Figure 4 is a fragmentary detail horizontal sectional view of the reciprocating cutter plate.

In the cutting and trimming of human hair, it is, in the majority of instances, desirable and essential to trim the hair at the hair line about 30 the scalp of the head in a tapering manner to effect a neat, attractive and well-groomed tonsorial appearance of the person. This operation, is ordinarily, accomplished by inserting the teeth of a comb between the ends of the hair, about the 35 hair line, and lifting the ends outwardly for trimming of the latter by means of a pair of scissors or shears, and which operation requires considerable time to perform.

Furthermore, in the foregoing method of tapering the hair, the services of a highly skilled tonsorial artist are required to obtain a presentable taper and trim to the hair.

40 My invention overcomes the foregoing disadvantages and enables an average skilled tonsorial artist to effect a presentable taper and trim to the hair and at the same time permits the operation to be consummated in a considerable less amount of time. It also eliminates the uncertain use of both the comb and scissors for performing the 45 tapering operation.

As practiced, my invention comprises a pair of hair clippers 5, comprising, the usual head plate 6 fashioned at the rear end thereof with a barrel 7 secured to the upper face of said head plate by 50 means of screws 8 extending through said head

plate and threadedly engaging a transversely extending flange 9 integrally formed on said barrel. Fixed on said barrel and extending upwardly and rearwardly therefrom is an arcuate shaped handle 10, the latter coacting with a movable handle 11 the lower end of which is pivotally mounted on the upper face of the flange 9 by means of a pivot screw 12 fixed in said flange 9 and extending upwardly therefrom. The lower end of the handle 11 is fashioned with an arm 13 extending forwardly of the screw 12 and spaced above the plate 6 and has formed on the outer end thereof a downwardly extending collar pin 14 for a purpose hereinafter more fully described.

10 The front end of the head plate 6 is fashioned with an outwardly and upwardly extending comb plate 15, the latter being disposed at an angle of approximately 45° relative to said head plate. The comb plate 15 gradually increases in thickness towards the upper and outer ends thereof and is 20 formed with spaced teeth 16 providing substantially triangular-shaped openings or slots 17 therebetween and having the respective face portion disposed adjacent the outer and upper ends of the teeth whereby when said comb plate is 25 moved upwardly on the scalp towards the top of the head, the hair line will be trimmed with a taper as hereinafter set forth, it being understood that a longer length of hair will be trimmed from the hair extending through said teeth at the upper and outer ends thereof than at the bottom end 30 of said teeth adjacent said head plate 6.

35 Mounted on the cutting face 15a of the comb plate 15, is a reciprocating cutting plate 18, the lower rear end of which is fashioned with a right angularly disposed upwardly extending section 19. The outer face of the plate 18, adjacent the junction with the section 19, is formed with a transversely extending groove 20 in which is seated, for relative sliding movement, the lower end of a 40 pressure plate 21 which adresses the section 19. The cutting plate 18 is also fashioned with a plurality of teeth 22 coacting with the teeth 16 to effect trimming of the hair upon reciprocation of the plate 18 as hereinafter set forth.

45 The upper end of the pressure plate 21 is formed with laterally extending lugs 23 through which extend bolts 24, the lower ends of the latter threaded into the comb plate 15 and the upper ends extending above the lugs 23 and equipped with adjustable wing nuts 25. Coil springs 26, carried by the upper ends of the bolts 24, interpose the nuts 25 and lugs 23 normally urge the pressure plate 21 into engagement with the cutting plate 18 and thereby maintain said 50

55

cutting plate 18 in working engagement with comb plate 15. Obviously, adjustment of the springs 26, through the medium of the wing nuts 25, serves to effect adjustment between the plates 5 15 and 18.

The sides of the cutting plate 18 are sufficiently inwardly slotted as at 27, through the ends of the groove 20, whereby to accommodate the bolts 24 and permit reciprocation of the plate 18 relative to said bolts.

The comb plate 15, at the sides thereof adjacent the lower end, is fashioned with a spaced pair of upwardly extending arms 28 formed on the upper ends thereof with forwardly extending 15 fingers 29 embracing the section 21, said section provided, on the sides thereof, with slots 30 for receiving said fingers in a manner to permit reciprocation of said section with said plate 18. The fingers 29 coact with the slots 30 to present 20 a lateral displacement of the plate 18.

The under face of the section 21 is formed with a rearwardly and horizontally extending arm 31, the rear end of which is bifurcated and receives therein the pin 14 whereby oscillation of the arm 25 13, through the medium of the handle 11, imparts reciprocating movement to the plate 18 for effecting cutting of hair disposed between the teeth 16 and 22.

The end of the barrel 7, adjacent the handle 30 11, is closed by a slidable disc 32 while the opposite end of said barrel is closed by a threaded plug 33. Within said barrel and interposed between the disc 32 and plug 33 is a coil spring 34 serving to urge said disc away from said plug. A 35 boss 35, formed on the handle 11 adjacent the lower end thereof, engages said disc 32 whereby said handle 11 is urged in a direction away from the handle 10. Obviously, when the handles 10 and 11 are grasped by the fingers and thumb of

the hand, and the handle 11 alternately moved towards the handle 10 by the fingers and released thereby and moved in the opposite direction by the action of the spring 34, will impart a reciprocating movement to the plate 18 through the 5 medium of the arms 31 and 13 as heretofore described.

From the foregoing, it will be apparent that I have provided a simple and efficient device for trimming the hair in a manner to effect a taper 10 thereof about the hair line on the scalp. It is to be distinctly understood, that various changes and modifications and arrangements of parts may be resorted to without departing from the spirit of the invention if within the scope of the 15 appended claim.

What is claimed is:

A device of the character described, comprising a head plate fashioned on one end with a comb plate, a coacting cutting plate slidably mounted 20 on said comb plate and fashioned with a transverse slot, said comb and cutting plates formed with coacting teeth for cutting hair extending therebetween, a pair of bolts fixed to said comb plate and receiving therebetween said cutting 25 plate, a pressure plate slidably mounted on said bolts and extending within said slot for maintaining said comb and cutting plates in cutting relation, means carried by said bolts and engaging said pressure plate for imparting pressure 30 thereto, adjustable means carried by said bolts and engaging said last mentioned means for regulating the pressure on said pressure plate, and means carried by said head plate and connected to said cutting plate for effect reciprocation of the 35 latter relative to said comb plate and said pressure plate.

JAMES CATINA.
